TAPE DISPENSER

Edwin F. Kusek, 5624 W. Windsor, Chicago, Ill.

Filed July 14, 1961, Ser. No. 65,917

Term of patent 14 years

(Cl. D74—1)

FIG. 1 is a front perspective view of a tape dispenser showing my new design, the broken line showing of the tape in this figure being for illustrative purposes only;

FIG. 2 is a rear elevational view thereof;

FIG. 3 is an end elevational view thereof;

FIG. 4 is a top plan view thereof; and

FIG. 5 is a sectional view taken along the line 5—5 of FIG. 1 showing the section along the top wall of the tape dispenser.

I claim:

The ornamental design for a tape dispenser, as shown and described.
